(57) **CLAIM**

The ornamental design for a chocolate egg, as shown and described.

DESCRIPTION

FIG. 1 is a top, front perspective view of our chocolate egg design.

FIG. 2 is an elevational view thereof, wherein the elevational view is identical from all sides.

FIG. 3 is a top plan view thereof;

FIG. 4 is a bottom plan view thereof;

FIG. 5 is a front elevational view of a segment of the design of FIG. 1, shown separately for clarity.

FIG. 6 is a rear elevational view of FIG. 5; and,

FIG. 7 is a left side elevational view of FIG. 5.
